UNITED STATES PATENT OFFICE

154,818

DESIGN FOR A HOUSING FOR A MICROFILM READER OR THE LIKE

Edward E. Strauss, Highland Park, Ill., assignor
to Bell & Howell Company, Chicago, Ill., a cor-
poration of Illinois

Application January 13, 1949, Serial No. 227

Term of patent 14 years

(Cl. D61—1)

To all whom it may concern:

Be it known that I, Edward E. Strauss, a citizen
of the United States, residing at Highland Park,
in the county of Lake and State of Illinois, have
invented a new, original, and ornamental Design
for a Housing for a Microfilm Reader or the like,
of which the following is a specification, reference
being had to the accompanying drawing, forming
a part thereof.

In the said drawing—

Figure 1 is a top plan view of a housing for a
microfilm reader or the like, embodying my new
design;

Figure 2 is a side elevation of the same;

Figure 3 is a bottom plan view of the same; and
Figure 4 is a front elevation of the same.

I claim:

The ornamental design for a housing for a
microfilm reader or the like, as shown.

EDWARD E. STRAUSS.
